UNITED STATES PATENT OFFICE

142,468

DESIGN FOR A SCRAPING TOOL

Harry E. Bremer, Milwaukee, Wis.

Application May 11, 1945, Serial No. 119,491

Term of patent 14 years

(Cl. D9—6)

To all whom it may concern:

Be it known that I, Harry E. Bremer, a citizen of the United States, residing at Milwaukee, in the county of Milwaukee and State of Wisconsin, have invented a new, original, and ornamental Design for Scraping Tool, of which the following is a specification, reference being had to the accompanying drawing, forming part thereof.

In the drawing:

Fig. 1 is a side elevational view of a scraping tool showing my new design;

Fig. 2 is a top view thereof; and

Fig. 3 is a bottom view.

I claim:

The ornamental design for a scraping tool, as shown.

HARRY E. BREMER.
